BANDAGE

Edward Gledhill, New York, N. Y.

Application October 18, 1945, Serial No. 623,094

5 Claims. (Cl. 128—156)

1

The present invention relates generally to bandages, but more particularly to a novel and improved as well as simplified construction of an adjustable bandage which will efficiently and adequately protect a sore or injury from outside pressure.

Heretofore it has been the practice to provide ready made commercial adhesive bandages which consist of multiple layers of gauze secured in the center of a band of adhesive plaster or surgical tape. In this type of bandage the gauze carrying the medication covers the sore or injury and the adhesive band holds the gauze bandage securely in place over the sore or injury. This type of bandage has many disadvantages, especially where the sore or injury is in a position where it contacts articles of clothing or where the injury occurs on parts of the body such as the hand, which frequently come in contact with outside objects. Then too, this conventional type of dressing or bandage often retards the rate of healing by actually increasing the friction and pressure. It is, therefore, one of the primary objects of the present invention to provide a novel and improved type of dressing or bandage which will not only overcome the disadvantages hereinabove pointed out, but which will also permit a wide latitude of adjustment and flexibility so as to afford a maximum application to the common type of sore or injury occurring on all parts of the body.

Another object of the invention is to provide a novel and improved construction of a ready made adhesive dressing or bandage in which a plurality of strips of gauze are positioned so that intermediate portions of certain of the strips lie contiguous to and are pressed into contact with an adhesive strip while the intermediate portions of certain other of these gauze strips are arranged to loosely contact the injury and are spaced from the first named strips of gauze with the co-extensive ends of all the strips of gauze being folded in a plurality of folds so as to form, in effect, oppositely disposed cushions or pillars attached to the central portions of the bandage to alleviate any pressure on the cut or injury.

A still further object of the invention is to provide a novel and improved adhesive dressing or bandage in which the opposite ends of a plurality of gauze strips are folded into a plurality of plies to form adjustable and spaced apart pillars so that the medicated portion of the gauze may loosely contact the cut or injury. These pillars are so formed and detachably attached to the adhesive strip that the height of either or both pillars may

2

be raised to quickly adjust the bandage to conform to the configuration of the surface of the body adjacent the sore or injury so that the pressure at all times on the injury may be alleviated.

5 A further object of the invention is to provide a novel and improved dressing or bandage having a freely suspended medicated gauze portion extending between the opposite ends of the gauze folded in the form of pillars whereby the pillars 10 may be not only adjusted in height, but adjusted for varying the spacing therebetween to accommodate bandages for various types and locations of injuries to the body.

These and other objects are accomplished by 15 providing a construction and an arrangement of the various parts in the manner hereinafter described and particularly pointed out in the appended claims.

Referring to the drawings:

20 Fig. 1 is a perspective view illustrating my improved type of dressing or bandage with the protective gauze or covering for the same in position to be removed therefrom;

25 Fig. 2 is a similar perspective view showing the manner in which the bandage is applied to the surface of the body for covering the wound or injury;

30 Fig. 3 is an enlarged longitudinal cross sectional view in a somewhat exaggerated form showing the manner in which the gauze strips are folded and positioned on the opposite sides of the center of the adhesive strip so as to support that portion of the gauze carrying the medication in loosely suspended form;

35 Fig. 4 is a similar longitudinal cross sectional view of the same bandage showing the manner in which the pillars may be adjusted for increasing the space therebetween and for raising the height of the individual pillars to accommodate 40 the bandage to bridge a relatively larger wound or injury; and

45 Fig. 5 is a similar cross sectional view of the same bandage showing the manner in which one of the pillars only is adjusted for height for adapting the bandage to conform to the curvature of the body where the injury occurs.

In illustrating one form of my invention, it will be noted that I employ a substantially rectangular form of adhesive plaster or tab generally indicated by the reference character 10. Attached to the adhesive side of the strip or tab 10 are a plurality of folded gauze strips so as to form, in effect, opposite cushioning pillars generally indicated by the reference characters 11 and 12. These pillars 11 and 12 are normally

spaced from each other at an equal distance from the transverse center of the adhesive strip or tab 10 so as to loosely suspend or bridge therebetween a plurality of strips of gauze generally indicated by the reference character 13 for carrying the medication and yieldingly contacting the wound or injury. A plurality of strips of gauze, as generally indicated by the reference character 14, are pressed against and contact the adhesive side of the plaster strip for securing the gauze as a whole in position on the tab 10. The cushioning pillars 11 and 12 and the intervening connecting portions 13 and 14 are made of a plurality (preferably four) lengths of gauze of substantially the same length. These separate lengths of gauze are designated by the reference characters 15, 16, 17 and 18. In order to form the cushioning pillars 11 and 12, the outer ends of the four strips of gauze, namely 15, 16, 17 and 18, are folded into three folds of four-ply, so as to form in effect sixteen plies of gauze to form the respective pillars. It will be obvious, of course, that a larger number of these strips of gauze than those indicated may be employed but for practical purposes, it has been found satisfactory in the use of the bandage to limit the same to the four strips of gauze disclosed in the drawings.

The construction of my improved bandage, normally assumes is like that shown in Figs. 1, 2 and 3 of the drawings, but the same is capable of adjustment so as to space the cushioning pillars at a greater distance apart and simultaneously increasing the height of the pillars, from the construction shown in Fig. 3 to the arrangement shown in Fig. 4. In this connection it will be noted that considerable difficulty is usually encountered in handling adhesive plaster or tape when necessity requires the detachment of the gauze from the tape in effecting an adjustment of the spacing between the pillars or in adjusting the height of the respective pillars. In order to facilitate the detachment of these pillars from the adhesive tape in making the adjustment for the spacing between the respective pillars 11 and 12, I have provided a means for neutralizing the adhesive at a point adjacent the outer base portions of the respective pillars so that substantially one-fourth of the area of the base of each of the pillars rests on this neutralized portion of the adhesive tape. Various methods or materials may be employed to provide such a neutralized area, but I preferably use a transverse strip of sterile paper as shown at 19. From the above it will be obvious that the outer ends of each of the pillars 11 and 12 shown in Fig. 3 of the drawings and resting upon the neutralized strip of paper 19 can be readily lifted to aid in detaching the pillar from the adhesive tape 10 so that when one fold is unwound, the remaining portions may be doubled or folded as shown at 20 and subsequently pressed into engagement with the adhesive strip 10 beyond the outer edges of the paper strip 19 as shown at 21 in Fig. 4 of the drawings. In this connection it will be noted that the spacing between the pillars 11 and 12 in Fig. 4 of the drawings is more than double in distance, and the height of the cushion pillars is increased to twenty-four plies of gauze, thereby giving greater height to the pillars and at the same time increasing the spacing therebetween to effectively take care of a relatively larger sore or injury with the same bandage.

In this connection it will be observed that the primary function of the protective pillars is to protect the sore or injury from outside pressure

so that under the circumstances, the farther away the protective pillars are from the injury, the higher or greater elevation these pillars should have. In other words, in order to secure the maximum comfort and utility from my new type of bandage, the protective pillars have to be adjustable so that they may be placed immediately adjacent the sore and the adjustment for height and spacing affords a complete flexibility of the bandage so that it may be made complementary or adaptable to the surface of the body where such adjustment is required.

In Fig. 5 of the drawings, only one of the pillars 12 is shown adjusted. In this case, the normal pillar 12 (as shown in Fig. 3 of the drawings) is adjusted to this form by detaching the same from the adhesive strip 10, folding the same in the center as shown at 22 so as to form in effect thirty-two plies of gauze, elevating this pillar to twice the height of the protective or cushioning pillar 11 in this figure. At the same time it will be noted that the spacing between the pillars is retained at the same distances as that disclosed in Fig. 3 of the drawings. When the bandage is adjusted in the manner disclosed in Fig. 5, it has special application to and may be used in connection with a rounded portion of the body where an injury or sore occurs, requiring that type of bandage to relieve the pressure thereon. The bandage is provided with the conventional protective strips 23 which are removed before applying the bandage to the sore or injury.

Summarizing the advantages and functions of operation of my improved bandage, it will be obvious that by providing detachable cushioning pillars on the opposite sides of the central portion of the adhesive plaster, by the simple expedient of employing a series of four strips of gauze of substantially the same length, folding the outer ends of these strips in the form of cushioning pillars with one portion of the intervening gauze loosely contacting the injury and the other intervening portion securing the gauze in position on the adhesive plaster, the manufacture and adjustment of the bandage is reduced to a simple operation. With this new bandage it will also be noted that the spacing between the pillars can be increased and at the same time, the height of the pillars can be also increased by the simple expedient of folding the pillar at the center thereof and securing the same in place at its extended position. This novel construction affords a wide range of flexibility so that the bandage can easily be adjusted to conform to a wound or injury occurring on any part of the body. It will further be observed that the bandages shown in the drawings can be manufactured in relatively long strips from which the individual bandages of varying widths may be severed.

While in the above specification I have described one embodiment which my invention may assume in practice, it will, of course, be understood that the same is capable of modification and that modification may be made without departing from the spirit and scope of the invention as expressed in the appended claims.

What I claim as my invention and desire to secure by Letters Patent is:

1. A bandage comprising a tab having adhesive on one side thereof and adapted to be applied adjacent a wound, a plurality of gauze strips having their opposite ends folded into a plurality of plies located on the opposite sides of the approximate transverse center portion of said tab and secured to the adhesive side thereof, certain por-

tions of said gauze loosely bridging the central portion of said tab, and certain other portions of said gauze attached to said tab.

2. A bandage comprising a tab having adhesive on one side thereof and a plurality of substantially uniform lengths of gauze strips having their opposite ends folded to form oppositely disposed cushioning pillars attached to said tab, intervening portions of said gauze strips extending between said pillars, certain of said intervening portions loosely suspended and carrying medication for application to the wound, certain other of said intervening portions attached to said tab.

3. A bandage comprising a strip of adhesive plaster, a plurality of gauze strips having their opposite ends folded to form cushioning pillars attached to and spaced on the opposite sides of the transverse center of said plaster strip, certain portions of said gauze strips loosely bridging said pillars and carrying a medication thereon, certain other gauze portions between said pillars engaging said adhesive plaster, and means for neutralizing certain portions of said adhesive plaster to facilitate the detachment of said pillars from said plaster strip.

4. A bandage comprising a strip of adhesive plaster, a plurality of plies of gauze strips having their opposite ends folded to form cushioning pillars on the opposite sides of the central portion of said adhesive strip, the intermediate portion of certain of said gauze strips loosely suspended

between said pillars, the intermediate portion of certain other of said gauze strips engaging said adhesive strip.

5. A bandage comprising a strip of adhesive plaster, a plurality of plies of gauze strips having their opposite ends folded to form cushioning pillars on the opposite sides of the central portion of said adhesive strip, the intermediate portion of certain of said gauze strips loosely suspended between said pillars, the intermediate portion of certain other of said gauze strips engaging said adhesive strip, and means for neutralizing certain portions of said adhesive plaster adjacent said pillars for facilitating the detachment of said pillars from said adhesive strip.

EDWARD GLEDHILL.
